Demag Aktiengesellschaft, Duisburg, Germany

Application January 27, 1933, Serial No. 653,791
In Germany February 5, 1932

8 Claims. (Cl. 214—138)

The invention relates to an instroke excavator provided with a shovel which is movable with respect to a pivoted haft-member, and can be tipped and emptied whatever the positions of the jib and haft-member. The cable which engages at the upper end of the haft-member is hereinafter referred to as the hoisting cable.

According to the invention the hoisting cable is provided with an extension or the equivalent which is connected to a gripping device of the brake, toggle, cable clamp or other type, and is also connected to gearing for directing the shovel, whereby when the extension of the hoisting cable is gripped, the shovel can be swung on the swinging of the haft-member while retaining its approximate position in space, the shovel being tipped and thus emptied when the extension of the hoisting cable is released.

The mechanism for directing the shovel consists essentially of a guiding quadrilateral which approximates to a pivoted parallelogram; this quadrilateral consists of the braking or gripping device, the lower arm of the haft-member, the shovel and the extension to the hoisting cable.

The instroke excavator according to the invention has the advantage that notwithstanding the range of movement of the shovel, two cables are in practice sufficient, namely the hoisting cable and the drag cable hereinafter described, that is to say there is the minimum number of cables and an extremely simple cable guide. Notwithstanding this simplification of construction, the shovel can be emptied in any position and accidental tipping of the shovel is effectively avoided.

The invention is diagrammatically illustrated by way of example in the accompanying drawing, in which

Figure 1 illustrates the method of controlling the shovel.

Figures 2 and 3 illustrate by way of example two constructions of the controlling apparatus.

Figures 4 and 5 show two operative positions of the excavator according to the invention.

Referring to Figure 1 of the drawing, the haft-member 3 of the shovel is rotatable about the pivotal axis 2 of the jib 1 of an instroke excavator. It is drawn by the drag cable 4 towards the excavator, while the haft-member 3 is moved by the hoisting cable 5 in the opposite direction. The hoisting cable 5 extends beyond the pulley 6 mounted at the upper end of the haft-member 3 and is connected to the shovel 7; this extension of the cable 5 is numbered 5a. The extension 5a may be held fast by a braking or clamping

member 8 provided on the jib 1. Thus, if the haft-member 3 is moved, the shovel 7 maintains its approximate angular disposition in space. This is due to the fact that the shovel is carried by a pivoted quadrilateral formed by the lower arm of the haft-member 3, the top edge of the side of the shovel 7, the extension 5a of the hoisting cable and that part of the extension of the jib between the pivotal axis 2 and the braking or clamping member 8. If the braking or clamping member 8 is released, the shovel 7 can be tipped by means of the cable 5, and turns about the axis 18 until it strikes against the stop 19.

Figures 2 and 3 illustrate in detail two constructions of braking device according to the invention. The reference numerals are for the most part the same as those in Figure 1. In Figure 2, the hoisting cable 5 is secured to a bell crank lever 10, which rocks about an axis 2, for example the axis of the haft-member 3, but independently of the haft-member itself. A cable, chain or belt 13, extends from the lower arm of the bell crank lever 10 to a drum 14, which drum is provided with a brake, the brake band being numbered 15. The brake band 15 is under the influence of a pressure medium cylinder and piston 16, which may operate for example with compressed air or steam, or water under pressure, or it may be controlled by an electro-magnet or by hand. The bell crank lever 10 is connected to the shovel 7 by a cable or rod 11, which is connected to the shovel at 12. If the brake holds fast the lever 10, and the drag cable 4 is slackened while the hoisting cable 5 is tensioned, the haft-member 3 is rocked by the hoisting cable 5, while the shovel 7 retains its approximately horizontal position because the parts 10, 3, 7 and 11 form a pivoted parallelogram. If on the other hand the brake 15 is released, the shovel 7 can be moved relatively to the haft-member 3.

The construction according to Figure 3 differs from that according to Figure 2 in that the lever 10 is replaced by a sector 17, the hoisting cable 5 passing over the arc 17a of the sector while the cable 13 which extends to the drum 14 lies on the channel 17b. The method of operation is substantially the same as that of the construction according to Figure 2.

Figure 4 illustrates the shovel shown in Figure 2 in the position reached near the end of the movement along the pit being excavated. The brake 15 is first released, the drag cable 4 is then tensioned, while the cable 5 is slackened. The shovel is thus caused to move inwardly and to be filled. The haft member 3 is now moved outwardly by

the winding in of the cable 5 and the slackening of the drag cable 4. The lever 10 is first secured by the brake band 15. If the haft-member 3 is rocked, the mechanism which determines the 5 position of the shovel consisting of the parts 3, 7, 10 and 11 causes the shovel to retain approximately its angular disposition in space, so that the final position is more or less as shown in Figure 5. The shovel does not rotate with the haft-member 3 and thus the earth or other material is prevented from falling out of the shovel when the haft-member 3 is moved. To empty the shovel 1 in the position illustrated in Figure 5, which need not be the extreme position, the brake band 15 is loosened so that the shovel 1 may be moved about the axis 18 to abut against the stop 19 by tensioning the cable 5.

Figures 1, 2 and 3 illustrate various modifications in construction of the braking or like device 20 but it will be understood that the invention is not limited to the constructions shown which are given merely by way of example.

The important point is that the movement of the shovel relatively to the haft-member is in all 25 positions under the control of the hoisting cable 5.

I claim:

1. An instroke excavator comprising a jib, a haft member supported by and rotatable upon the said jib, a shovel movable relatively to and supported by the haft member, a braking element adjustable upon the said jib independently of the said haft member, a hoisting cable connected with the braking element and engaging the haft member, and a link between the braking 35 element and the shovel such that the braking element being retained in fixed relation to the jib the haft member may be swung by the hoisting cable while the shovel retains its angular disposition in space.
2. An instroke excavator comprising a jib, a haft member pivoted at a point intermediate its ends upon the jib, a braking element upon said jib to which the haft member is relatively rotatable, means upon said jib for operating said braking element, a shovel pivoted to one end of the 40 said haft member, a connection between the braking element and the shovel at a radius from the pivotal point of the shovel, a drag cable connected to said haft member, and a hoisting cable connected to the said braking element and engaging the haft member.
3. An instroke excavator comprising a jib, a haft member pivoted at a point intermediate its ends upon the jib, a braking element rotatable 45 about the pivot of the haft member upon the said jib, a brake mechanism upon the said jib con-

trolling the rotation of the braking element, a shovel pivoted to one end of the said haft member, a link connected between the braking element and the shovel at a radius from the pivotal point of the shovel, a drag cable connected to said haft member, and a hoisting cable connected to said braking element and engaging the haft member.

4. An instroke excavator according to claim 3, in which the braking element is subjected to the 10 control of the braking mechanism through a connection which engages the braking element with a leverage distinct from that applied by the braking element through the link to the shovel.

5. An instroke excavator comprising a jib, a 15 haft member movable relatively to the said jib, a shovel movable relatively to the haft member, braking means upon the jib, mechanism for controlling the movement of the shovel including an element in extension of the hoisting cable and 20 the said braking means whereby when the said element is braked by the braking means and the haft member is swung the shovel may be correspondingly moved while retaining its angular disposition in space and may be tilted when the said 25 element is released by the braking means.

6. An instroke excavator according to claim 5, in which the mechanism directing the shovel comprises a quadrilateral linkage consisting of 30 the braking means, the haft member, the shovel and the said element.

7. An instroke excavator with mechanism for directing the shovel, including a shovel haft to which the shovel is pivoted, a hoisting cable operatively linked or coupled to the shovel at a position distant from the pivotal axis to permit the hoisting cable to be used for tipping the shovel, and a braking device which when operative restrains the shovel from tipping and causes it to remain approximately in the same angular 40 position in space when the haft swings.

8. An instroke excavator comprising a jib, a shovel, a directing mechanism inclusive of a haft member pivoted to the jib and having the shovel pivoted thereon and by which the shovel is directed, a hoisting cable, a shovel control member associated with, but movable independently of, the haft member, and a braking device, the said hoisting cable being connected with the control member which is linked or coupled to the shovel 45 for the tilting of the shovel by the hoisting cable and the braking device being applied to the said control member so that when operative it retains the shovel approximately in the same angular disposition in space when the haft member swings. 50 55

HEINRICH SIEBERT.
